(57) **CLAIM**

The ornamental design for a shaver as shown and described.

DESCRIPTION

FIG. 1 is a front perspective view of a first embodiment of a shaver, showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a rear perspective view thereof.

FIG. 9 is a front perspective view showing a second embodiment of a shaver, showing the new design;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof;

FIG. 15 is a bottom plan view thereof; and

FIG. 16 is a rear perspective view thereof.

FIG. 17 is a front perspective view of a third embodiment of a shaver, showing the new design;

FIG. 18 is a front elevational view thereof;

FIG. 19 is a rear elevational view thereof;

FIG. 20 is a left side elevational view thereof;

FIG. 21 is a right side elevational view thereof;

FIG. 22 is a top plan view thereof;

FIG. 23 is a bottom plan view thereof; and

FIG. 24 is a rear perspective view thereof.

FIG. 25 is a front perspective view of a fourth embodiment of a shaver, showing the new design;

FIG. 26 is a front elevational view thereof;

FIG. 27 is a rear elevational view thereof;

(Continued)

FIG. 28 is a left side elevational view thereof;
 FIG. 29 is a right side elevational view thereof;
 FIG. 30 is a top plan view thereof;
 FIG. 31 is a bottom plan view thereof; and,
 FIG. 32 is a rear perspective view thereof.
